[57] **CLAIM**

The ornamental design for a hand-held nut driver, as shown and described.

DESCRIPTION

FIG. 1 is a perspective view of a hand-held nut driver showing the first embodiment my new design, the handle shown in phantom outline is for illustrative purposes only and forms no part of the claimed design;

FIG. 2 is a top plan view thereof;

FIG. 3 is a right side elevational view thereof, the left side elevational view being a mirror image;

FIG. 4 is a front elevational view thereof;

FIG. 5 is a rear elevational view thereof;

FIG. 6 is a bottom plan view thereof; and,

FIG. 7 is a fragmented front elevational view of the second embodiment, the top plan view and the rear, right and left side elevational views are identical.
